(57) CLAIM

An ornamental design for a sports cap shaped pet house or carrier, substantially as shown and described.

DESCRIPTION

FIG. 1—is a perspective view of a sports cap shaped pet house or carrier.

FIG. 2—is a back view thereof.

FIG. 3—is a front view thereof.

FIG. 4—is a right side view thereof.

FIG. 5—is a left side view thereof.

FIG. 6—is a top view thereof; and,

FIG. 7—is a bottom view thereof.

The broken lines are for illustration only and form no part of the claimed design. The broken lines on both sides of the seams and on the visor of the cap are representative of stitching and form part of the claim.
